UNITED STATES PATENT OFFICE.

FREDERICK L. BECKER, OF CHICAGO, ILLINOIS.

DESIGN FOR AN UPHOLSTERING-PIN.

56,580.

Specification for Design.

Patented Nov. 16, 1920.

Application filed October 25, 1919. Serial No. 333,406. Term of patent 14 years.

To all whom it may concern:

Be it known that I, FREDERICK L. BECKER, a citizen of the United States, and residing in the city of Chicago, county of Cook, and State of Illinois, have invented a new, original, and ornamental Design for an Upholstering-Pin, of which the following is the specification, reference being had to the accompanying drawings, forming a part thereof.

In the drawings:

holstering pin illustrating the design of my invention.

Fig. 2 is a bottom plan view thereof.

Fig. 3 is a side elevation thereof.

I claim:

An ornamental design for an upholstering pin as shown.

FREDERICK L. BECKER.
